UNITED STATES PATENT OFFICE.

FRANK J. McNULTY, OF LOWELL, ARIZONA.

RESILIENT WHEEL.

1,277,330.

Specification of Letters Patent. Patented Aug. 27, 1918.

Application filed October 25, 1917. Serial No. 198,430.

To all whom it may concern:

Be it known that I, FRANK J. McNULTY, a citizen of the United States, residing at Lowell, in the county of Cochise and State 5 of Arizona, have invented certain new and useful Improvements in Resilient Wheels; and I do hereby declare the following to be a full, clear, and exact description of the invention, such as will enable others skilled 0 in the art to which it appertains to make and use the same.

The present invention relates to resilient wheels, and more particularly to that class known as the inner cushioned rim type.

15 The object is to provide a mechanical structure of resilient wheel which possesses the same resiliency and shock-absorbing features of the pneumatic tire, and at the same time overcomes all of the disadvantages incident to the use of pneumatic tires, such as 20 punctures, blow-outs, and the high cost of maintenance of the same.

The invention also aims at the provision 25 of a resilient structure embodying relatively few parts to which access may be readily gained for the renewal of parts when worn; the removal of the outer rim and the tread to renew the latter, and to provide a structure which requires no adjustment and 30 which at the same time is capable of responding to varying loads within the limits of the strength of the wheel.

With these and further objects in view, as will in part hereinafter become apparent 35 and in part be stated, the invention comprises certain novel constructions, combinations and arrangements of parts as subsequently specified and claimed.

In the accompanying drawings,—

40 Figure 1 is a side elevation, partly in section, of a resilient wheel constructed according to the present invention.

Fig. 2 is an enlarged, transverse section taken on the plane indicated by line 2—2 45 of Fig. 1 through the outer portion of the wheel, showing the parts assembled.

Fig. 3 is a detail, perspective view, enlarged, of one of the guides employed.

Fig. 4 is a detail, perspective view, enlarged, of one of the slide blocks employed.

Fig. 5 is a view similar to Fig. 3 disclosing a modified construction of the guide and a modified view of slide block for the same.

Fig. 6 is a like view disclosing a further

modification in the structure of the guide 55 and blocks.

Fig. 7 is a like view showing a still further modified form of the guide and slide block.

Fig. 8 is a fragmentary, enlarged side 60 view of a pair of the sliding blocks and the adjacent guides therefor, the view showing a means for compressing the blocks together.

Fig. 9 is an outer edge view of the same, 65 the outer rim being removed.

Referring to the drawings, the invention is illustrated as applied to a wheel body of ordinary construction, and wherein A designates a hub having radiating spokes B upon the ends of which is supported a felly C. 70

Mounted upon the felly C is an inner rim 10, which preferably has an annular undercut rib 11 on its inner face adapted to seat upon the felly C and retained detachably thereon by clamping rings 12 secured by 75 bolts 13 or the like to the opposite sides of the felly C, as shown in Fig. 2. The rings 12 have at their outer, marginal edges in-turned annular flanges or beads which interlock with the annular bead 11 of the inner 80 rim 10.

Fixed upon the inner rim 10 is a plurality of guides 14 which, as shown in Fig. 3, may comprise castings of substantially inverted V-shape, provided with attaching lips 15 at 85 opposite ends adapted to rest upon the outer peripheral surface of the rim 10 and conforming to the curvature thereof. The guides are secured to the rim 10 by rivets 16, or the like, which pass radially through 90 the ends of the guides and through the rim 10 and its bead 11, the opposite ends of the rivets 16 being headed and counter-sunk in the faces of the guides and the rim. In the form shown in Fig. 3, the guides 14 have 95 longitudinally-extending dove-tail tongues 17, which are preferably interrupted at the apex or highest point of each guide. Slide blocks 18, such as shown in detail in Fig. 4, are mounted to slide on the opposite sides 100 of the guides 14 and have dove-tail grooves 19 in their inner faces to receive the tongues 17 therein for interlocking the blocks to the guides. The blocks 18 are of less length than the inclined faces of the guides 14 and are adapted to move longitudinally over the inclined faces to a limited extent. As shown in Fig. 1, the guides 14 are placed upon the

105

rim 10 in end to end abutting relation, and the blocks 18 are arranged in pairs on the adjacent faces of the guides 14 which converge inwardly toward the adjacent abutting 55 ends of the guides.

Each pair of blocks 18 is provided with means yieldingly urging the blocks apart to ride upon and outwardly over the inclined faces of the guides 14. One form of 10 means is disclosed in the drawings, wherein a bumper block 20 is employed which is formed of rubber, or the like, reinforced by a pair of semi-elliptic springs 36 embedded in the bumper blocks and extending transversely to the longitudinally axis of the slide blocks 18, and having their bowed portions facing the blocks 18. The resilient blocks 20 are further strengthened by the provision of a perforated plate 37 which is also 15 embedded in the block between the springs 36, the plate being substantially of a width and height equal to the cross sectional area of the block 20. The adjacent ends of the blocks 18 are provided with one or more 20 registering apertures 21 forming a socket or sockets adapted to receive therein the opposite ends of compression springs 22, which pass through registering apertures formed in the resilient blocks 20, and serve as auxiliary 25 means thereto for holding the blocks 18 of each pair apart. The reinforcing plates 37 are suitably apertured for the passage of the springs 22 therethrough, the springs extending longitudinally through the bumper 30 block 20 and projecting beyond the ends thereof for engagement in the seats or recesses 21. Preferably, resilient disks 23 and superposed fiber disks 24 are placed in the inner ends of each socket 21 to receive the 35 adjacent ends of the springs 22 thereagainst. 40

It is, of course, understood that the blocks 18 may be provided with one or any number of sockets dependent upon the load to be carried and the size of the wheel, and that a corresponding number of yielding separating means for the blocks 18 may be provided.

These guides and blocks may be made in various forms, and as shown in Fig. 5, the 50 guide 14^a has flat, inclined faces with lateral, marginal, upstanding guide flanges 17^a receiving therebetween the slide blocks 18^a which have a correspondingly formed flat base or inner face.

55 In Fig. 6, a further modification is disclosed wherein the guide 14^b has longitudinally concaved faces at opposite ends which are inclined inwardly toward the ends of the guide and which have the lateral, marginal flanges 17^b outstanding therefrom and conforming to the curvature thereof. The slide blocks 18^b in this instance have bases conforming to the curvature of the inclined faces of the guide 14^b.

60 65 A still further modification is disclosed

in Fig. 7, wherein the guide 14^c is substantially of arcuate form from end to end, and has the upstanding marginal flanges 17^c conforming to the curvature of the guide. In this instance the slide blocks 18^c have 70 longitudinally concaved bases adapted to lie snug against the convexed opposite end portions of the guide 14^c.

In all of these instances, the opposite ends of the guides present bearing faces which 75 are inclined inwardly with respect to the hub of the wheel toward the opposite ends of the guide.

The slide blocks 18 are adapted to carry an outer rim 25, which, as shown, may be 80 in the form of an annular band of a width equal substantially to that of the inner rim 10. The outer faces of the blocks 18 are curved longitudinally to conform to the inner periphery of the outer rim 25 and are 85 adapted to slide thereagainst when sufficient pressure is brought on the outer rim 25 opposite the blocks. The rim 25 carries a tread portion which is preferably made up of a number of wooden segments or blocks 26 90 seated upon the outer periphery of the rim 25 and upon which is mounted a tread 27 of any suitable material or composition, and which may comprise a corded tread or a solid rubber strip. Nails 28, or the like, may be secured through the tread 27 and into the wooden blocks 26 for uniting the parts 95 into a homogeneous tread structure.

The tread structure is retained upon the outer rim 25, and the latter is held within 100 the general plane of the wheel, by clencher plates 29 of annular form secured by bolts 30, or the like, to the opposite edges of the outer rim 25 and extending beyond the inner and outer surfaces of the rim. The inner 105 marginal edges of the clencher plates 29 terminate substantially flush with the inner surface of the inner rim 10, and the outer marginal edges of the plates 29 terminate substantially flush with the peripheral row 110 of wooden blocks 26. The inner opposite faces of the plates 29, outwardly of the rim 25, have serrations or teeth 31 extending annularly upon the plates 29 and adapted for biting engagement in the opposite edge portions of the blocks 26 to firmly hold the latter to the outer rim 25.

115 For the purpose of facilitating the removal of the outer rim 25 from the blocks 18, after one or both of the clencher plates 29 have been removed, the blocks 18 are provided, in one or both sides, with tapped openings 32 for the reception of machine screws 33, shown in Figs. 8 and 9. The screws 33 have unthreaded bearing portions 120 immediately adjacent their heads for the reception of the correspondingly apertured ends of oppositely threaded rods 34 of a turn-buckle which may be applied to each 125 pair of blocks 18. The sleeve 35 of the turn- 130

buckle is adapted to connect the rods 34 and the latter are preferably offset to space the sleeve 35 laterally from the adjacent resilient block 20. The turn-buckle is adapted 5 to be manipulated for drawing a pair of the blocks 18 together and compressing the block 20 and the adjacent springs 22 to thus reduce the diameter of the tread surfaces of the blocks 18 and admit of the sliding of 10 the outer rim 25 with its parts into and out of the plane of the wheel. The turn-buckles are temporarily used during the assembling and the separation of the parts of the wheel, and it is readily seen that access may be eas- 15 ily had to any desired pair of the blocks and to the parts tending to separate the same without disturbing the remaining blocks of the wheel. The parts of the wheel may be formed of any suitable material, but prefer- 20 ably the slide blocks 18 are formed of fiber to prevent undue wear incident to the frictional contact of the blocks with the outer rim 25 and the guides 14.

It is, of course, understood that the de- 25 tails of design and substitution of parts may be varied without departing from the spirit of this invention in order to meet various conditions found in the manufacture and use of the wheel, all of these changes 30 being contemplated within the scope of the appended claims.

What is claimed is:—

1. In a resilient wheel, the combination, of an inner rim, an outer rim, blocks ar- 35 ranged between the rims and slidably en- gaging with one of them, guides carried by the other rim having inclined faces engaging the blocks to move the same in pairs toward each other when the rims are compressed, 40 and means for yieldingly separating the blocks of each pair.

2. In a resilient wheel, the combination, of inner and outer rims, inclined guides ar- 45 ranged on one of the rims with the bearing surfaces thereof converging toward each other and toward the adjacent face of the rim, pairs of inclined blocks mounted on the guides and adapted to bear against the other rim, and resilient means arranged be- 50 tween each pair of blocks to yieldingly hold the same in separated position and at the upper portions of the guides.

3. In a resilient wheel, the combination, of inner and outer rims, a plurality of 55 guides arranged peripherally upon one of the rims and having inclined faces con- verging toward the adjacent face of the other rim, a plurality of blocks having in- clined bases seating on the guides and hav- 60 ing curved outer faces engaging the ad- jacent peripheral surface of said other rim, cushioning means arranged between each pair of blocks to urge the latter upwardly on the inclined faces of the guides and 65 against said other rim, and means for re-

taining the outer rim from lateral displace- 70 ment from the blocks.

4. In a resilient wheel, the combination, of inner and outer rims, inclined guides mounted on one of the rims, slideable blocks 75 mounted on the guides and engaging the other rim, cushioning elements arranged between each pair of blocks to hold the latter against said other rim and upon the outer ends of the guides, a tread structure 80 mounted on the outer rim, and clencher plates secured to the opposite edges of the outer rim and extending outwardly against the tread structure to retain it to the outer rim and extending inwardly at the oppo- 85 site sides of the inner rim to hold the outer rim to the blocks.

5. In a resilient wheel, the combination, of inner and outer rim, a peripheral row 90 of guides mounted on one of the rims and having alternately inclined bearing faces, pairs of blocks seated on said inclined faces and bearing at their outer sides against the other rim, cushioning blocks arranged be- 95 tween the pairs of sliding blocks to hold the latter in spaced relation and against the other rim, and auxiliary springs arranged between the blocks of each pair to augment the cushioning blocks and strengthen the structure.

6. In a resilient wheel, the combination, of inner and outer rims, guides secured to the inner rim in end abutting relation and having oppositely inclined bearing faces at 100 their ends, blocks slidably mounted on said bearing faces and adapted to move thereon toward and from each other and bearing at their outer sides against the outer rim, said blocks having registering sockets in their adjacent ends, springs seated at opposite ends in the sockets of the blocks to urge the latter apart, and means for retaining the outer rim from lateral displacement from the blocks.

7. In a resilient wheel, the combination, 110 of inner and outer rims, a plurality of guides secured in end to end abutting relation upon the peripheral surface of the inner rim, a block mounted upon the outer face of each guide and adapted to slide longitudinally 115 thereon, the outer faces of said guides being inclined to move the blocks outwardly when slid on the guides, said blocks bearing at their outer faces against the outer rim to re- 120 tain the latter concentric about the inner rim, cushioning means arranged between the adjacent ends of each pair of blocks to urge the latter outwardly from the inner rim, and detachable means carried by one of the rims for holding the outer rim from lateral 125 displacement from the blocks.

8. In a resilient wheel, the combination, of inner and outer rims, inclined guides mounted upon one of the rims, blocks slid- 130 ably mounted on the guides and engaging

the other rim, cushioning means engaging the blocks to urge the latter outwardly upon the guides and against said other rim, and means for retaining the blocks and the outer rim from lateral displacement with respect to the inner rim.

9. In a resilient wheel, the combination of inner and outer rims, movable members carried in pairs by one rim and engaging 10 the other rim, and a cushion element engag-

ing between each pair of said members to urge the latter apart and toward said other rim.

In testimony whereof I affix my signature in presence of two witnesses.

FRANK J. McNULTY.
